UNITED STATES PATENT OFFICE

GEORGE I. ROCKWOOD, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS

LOCKING MEMBER FOR SPRINKLER HEADS

Application filed December 18, 1929. Serial No. 415,008.

This invention relates to a locking member or strut adapted for use in sprinkler heads and for other similar purposes.

Such members are designed to yield upon substantial rise in temperature of the surrounding atmosphere, and it is the object of my invention to provide a locking member or strut for such purposes in which the thermal element, being held under light compression, thereby permits a low-melting alloy to be utilized in an arrangement of parts which promotes sensitiveness in operation. To this end the thermal element and its supporting structure is directly exposed to a rising current of hot air when the device is in use in a sprinkler head.

My invention further relates to arrangements and combinations of parts which will be hereinafter described and more particularly pointed out in the appended claims.

A preferred form of the invention is shown in the drawing, in which

Fig. 1 is a side elevation of a sprinkler head embodying my improvements;

Fig. 2 is a sectional side elevation of my improved locking member;

Fig. 3 is a plan view thereof, looking in the direction of the arrow 3 in Fig. 2;

Fig. 4 is an end elevation thereof, looking in the direction of the arrow 4 in Fig. 2;

Fig. 5 is a perspective view of the retaining device;

Fig. 6 is a bottom view, looking in the direction of the arrow 6 in Fig. 2;

Fig. 7 is a perspective view of the thermal element; and

Fig. 8 is a side elevation showing the parts released.

While adaptable to fire door links and other uses, my improved locking member is particularly designed for use in sprinkler heads, a common form of which is shown in Fig. 1.

A threaded member or nipple 10 is provided with a cap or closure 12 functioning as a valve held in place by a post 14 engaging one end of a lever 15. A locking member or strut is interposed between shoulders at the lower end of the post 14 and at the outer end of the lever 15. A compression

screw 17 engages the upper side of the lever 15 at a point slightly out of alignment with the post 14. The screw 17 and a spreader plate 18 are mounted on a frame structure 20, projecting upward from the threaded member or nipple 10.

My present invention is not concerned with the general structure of the sprinkler head but relates more specifically to the structure of an improved locking member or strut for holding the post 14 and lever 15 in position to firmly seat the cap or closure 12.

My improved locking member comprises two thrust members 30 and 31, commonly disposed face to face as indicated in Fig. 2, with one end portion 32 of the member 30 engaging a shoulder 33 on the member 31. The thrust member 30 has a portion 35 projecting outward substantially perpendicular to one face thereof for a purpose to be described.

The member 30 also has an opening 37 therein through which extends an end portion of a retaining member 40. The body portion of the member 40 extends alongside and substantially parallel to the portion 35 of the thrust member 30. An offset projection 42 at one end of the member 40 is seated in a pocket or recess 43 in the member 30 at one side of the opening 37. The member 40 also has a lug or projection 44 engaging the outer face of the thrust member 31 and holding it in contact with the thrust member 30.

A thermal element 50 is inserted between the portion 35 of the member 30 and the retaining device 40. When pressure is applied at the ends of the locking member, as indicated by the arrows *a* and *b* in Fig. 2, it is obvious that the thermal element 50 will be held in compression.

I am thus enabled to use a low-melting solder, such as a mercury alloy, which could not be used in the ordinary construction where the thermal element is under tension instead of compression, as such low-melting alloys will yield and flow plastically under continued tension or even under continued shear, at normal temperatures. When, however, such solder is under compression be-

tween comparatively large surfaces, this cold flowing practically ceases.

In order to prevent both corrosion and possible displacement of the parts, I commonly apply small amounts of solder, as indicated at *s*, to retain the several parts in assembled relation. The members 35 and 40 are preferably recessed, as indicated at *ss*, so that, the walls being thinner, the device will be more quickly responsive to a rise in temperature.

Reference to Fig. 1 will show that when my improved locking member is in working position, the thermal element projects downward from the locking member directly into the path of a rising current of overheated air such as is indicated by the arrows *c* in Fig. 1. Consequently my improved locking member is very quickly responsive to a rise in temperature.

I find it desirable to form the thermal element with a recessed portion 56, as indicated in Fig. 7, as the greater part of the pressure is received by that part of the thermal element adjacent the outer ends of the members 35 and 40. With the recessed construction, less solder must be melted before the device will operate, while the interior space unfilled by solder is nevertheless not exposed to any corroding influences from without which might otherwise prevent movement of the retaining device 40.

An important result of the arrangement of the component parts of the strut as shown is that there is practically no diminution of the thrust of the compression screw 17 on the lever 15 and the ends of the locking member until after the angular movement of the part 40 has entirely released the thrust member 31. At that instant all restraint is suddenly removed and hence the force of the screw becomes dynamic through the spring of the frame and the lever, post and strut are jerked free from each other even if corrosion has set in to an extent sufficient, in the absence of such suddenly applied force, to prevent the release of the parts. When the solder melts, the parts separate, as indicated in Fig. 8, allowing the sprinkler to open and to become operative in the usual manner.

Having thus described my invention and the advantages thereof, I do not wish to be limited to the details herein disclosed, otherwise than as set forth in the claims, but what I claim is:—

1. In a sprinkler head, a locking member comprising two thrust members disposed face to face and having portions abutting endwise, one of said thrust members having an opening therein and having a portion projected outwardly from one face thereof, a retaining device extending through said opening and alongside said outwardly projecting portion and having offset lugs engaging oppositely disposed faces of said two thrust members and a thermal element held in compression

between said retaining device and said outwardly projecting portion of said thrust member, when arranged in operative position in said sprinkler head.

2. In a sprinkler head, a locking member comprising two thrust members disposed face to face and having portions abutting endwise, one of said thrust members having a portion projecting outward from one face thereof, a retaining device for said thrust members positioned alongside said outwardly projecting portion, and a thermal element held in compression between said retaining device and said projecting portion, when arranged in operative position in said sprinkler head.

3. The combination in a locking member as set forth in claim 2, in which the thermal element is recessed to effect a substantially U-shaped section.

4. In a sprinkler head, a locking member comprising two thrust members positioned face to face and having portions abutting endwise, a retaining device for said members, and a thermal element held in compression between said retaining device and a portion of one of said thrust members, when arranged in operative position in said sprinkler head, said locking member remaining substantially unchanged in length until said thermal element has melted and said retaining device has completed its releasing movement.

5. In a sprinkler head, a locking member comprising two thrust members positioned face to face and having portions abutting endwise, a retaining device for said members, and a thermal element formed of a low melting alloy and held in compression between said retaining device and a portion of one of said thrust members when said parts are arranged in operative relation in a sprinkler head, said retaining device having a pivotal releasing movement about one end thereof when said thermal element melts and retaining said thrust members in abutting relation until said pivotal movement is substantially completed.

In testimony whereof I have hereunto affixed my signature.

GEORGE I. ROCKWOOD.
